UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,359,019.

Specification of Letters Patent. Patented Nov. 16, 1920.

Application filed January 4, 1918. Serial No. 210,262.

To all whom it may concern:

Be it known that I, JOHN H. BELL, a citizen of the United States, residing at South Orange, in the county of Essex and State of New Jersey, have invented certain new and useful Improvements in Telegraph Systems, of which the following is a full, clear, concise, and exact description.

This invention relates to systems of communication, and more particularly to systems of simultaneous telegraphy and telephony.

The principal object of this invention is to provide an improved organization of apparatus for the reception of telegraphic impulses.

In applying the so-called vibrating or self-aiding relay of Gulstad to telegraphic service over circuits which are also used for telephonic communications, inductive effects emanating from the local or vibratory control circuits of such a relay may unfavorably affect the telephonic service.

In order to overcome such disturbances in the telephonic devices the present invention contemplates an arrangement wherein the electrical and magnetic paths which are associated with the exterior or line circuits of a self-aiding relay will be inductively distinct from the corresponding paths of the local or vibrating circuits of the same relay device.

This invention is illustrated diagrammatically in the accompanying drawing in which only so much of a telegraphic equipment has been shown as will be necessary to a clear understanding of the invention.

In describing this system, an inductively balanced telephone circuit designated by the reference character A terminates in a duplex equipment which comprises bridge or ratio arms B, artificial line devices C, and an impulse receiving relay D. The relay D is composed of two sections; the first section E is provided with windings 1 and 2 which are connected serially between the circuit of one conductor 40 of the metallic telephone line and the artificial line to form a derived circuit with respect to the bridge arm resistances 25 and 26, while windings 3 and 4 of this relay section are similarly connected from the circuit of the other conductor 41 of the telephone circuit. For the second relay section F, a circuit extends from a grounded resistance unit 13 through the

windings 11 and 12 and a condenser 14 to ground. A conductor 18 is connected intermediate the coils 11 and 12 and extends to a moving contact member 5. The member 5 is adapted to reciprocate between two oppositely positioned contact stops, and it will be understood that the conventional plus and minus signs respectively placed beside these stops indicate that they are to be connected with correspondingly poled and grounded batteries. A lead 17 also connected to the relay tongue 5 may be considered as extending to a suitable telegraph receiving device, or to circuits suitable for repeating into another telegraphic circuit.

Referring more particularly to the structure of the relay, a suitably pivoted shaft 6 carries, in addition to the relay tongue member 5, armature members 7 and 8 which work in the upper and lower gap-spaces, respectively, present in the magnetic core circuit of the coils 1—4 of the section E, and armature members 9 and 10 positioned to similarly work in the gap-spaces of the magnetic core energized by the coils 11 and 12 of the section F. Permanent magnets 15 and 16 serve to polarize the armatures of the first and second sections, respectively. For purpose of description it will be assumed that if a positive current were to enter the coil 1 and emerge from the coil 4 the armatures 7 and 8 would bias to the left-hand side, in which position the tongue 5 would engage the positively marked contact stop, while a reversal of such current direction would bias the armatures to the right-hand side, thereby causing the tongue 5 to connect with its negatively marked stop. At the section F the condenser 14 will receive either a positive or a negative charge depending upon whether the tongue 5 is on its positively or its negatively energized contact stop. Since the condenser 14 may be charged only by current routed over the conductor 18 the circuits of the coils 11 and 12 are usually proportioned to provide that the steady current present in the coil 11, by way of the resistance 13 to earth, will be differentially overcome by the current through the coil 12 while it is flowing to charge the condenser 14. At such condenser charging instants, therefore, the coil 12 exerts influence on the associated armatures 9 and 10 to increase the pressure on the stop through which the condenser may be charg-

ing. Immediately on cessation of the condenser charging current through the coil 12, however, the steady current in the coil 11 becomes effective to stress the armatures 9 and 10 toward their opposite position. For example, if the tongue 5 is against its positively energized stop all of the armatures 7-10 will be to the left-hand side in establishing this position of the tongue, and positive current over the conductor 18, after charging the condenser 14, will cause the coil 11 to exert a limited force which will have a tendency to move the armatures 9 and 10 to the right-hand position. When the tongue 5 is in connection with its negative stop current of that polarity will act inversely through the coil 11 to stress the armatures 9 and 10 from the right to the left. It will be noted that the resistance 13 and the condenser 14 are each of an adjustable type. Therefore it is possible to vary the electrical time-constant of the circuits through the coils 11 and 12 to secure the differential aiding effect already mentioned and also to permit the coil 11 to be influenced by the steady current only to the extent that the normal polarizing stress of all the armatures 7-10 will be substantially neutralized. During the time the tongue 5 is passing from one to the other of its stops the condenser 14 discharges serially through the windings 11 and 12 and the resistance unit 13. The effect of such discharges are accumulative in the coils 11 and 12 and always in a direction to cause the armatures 9 and 10 to aid the armatures 7 and 8 in moving the tongue 5 to its opposite position. To make this clear, if the tongue 5 is, say, against its negative stop and an impulse of positive line current enters at the coil 1, the armatures 7 and 8 will be stressed to cause the tongue 5 to separate from its negative stop. The condenser 14 having received a charge from the negative source at the time the tongue was in contact with that stop, it follows that so soon as the tongue breaks this connection the condenser will discharge, thereby causing the coils 11 and 12 to move the armatures 9 and 10 from the left to the right and will thereby assist the armatures 7 and 8 in moving the tongue 5 across its gap-space to the opposite or positive contact stop. In order that the section E may be inductively distinct both electrically and magnetically from the section F an insert 19 of non-magnetizable material, as brass or aluminum, is placed intermediate the two sections of the relay in establishing mechanical continuity of the shaft 6.

60 Referring more particularly to the operating features of the system, a telegraph transmitter represented by a key 31 is arranged to alternately establish two oppositely poled batteries 32 and 33 in accumulative relation with the conductors 40 and

41 of the telephone line A, and at the same time with the artificial line C, it being understood that by means of the adjustable resistances and the adjustable condensers which comprise the artificial line that the 70 electrical characteristics of this line may be calibrated to correspond with the electrical characteristics of the metallic or real line A. A telephone equipment T is connected in bridge on the line conductors 40 and 41, 75 the associated condensers, grounded impedance units and impedance units 29 and 30 restrict the telegraphic currents to their proper paths and prevent other than telephonic currents reaching the telephone de- 80 vices.

It will be understood that a distant station (not shown) on the line A is provided with an equipment identical to the equipment shown in the drawing. Therefore telephonic communication may be carried on between the telephone equipments T and the distant telephone instruments. telegraphic messages may be sent by the transmitting key 31 to be reproduced through a distant 90 line relay corresponding with the relay D, and a distant transmitter equipment corresponding with the key 31 and associated batteries may control the line relay D in sending telegraphic signals from the distant 95 to the present station.

In describing operations whereby telegraphic signals may be received from the distant station a more ready understanding of the relation of the relay D may be had 100 by disregarding, for the moment, the presence of the transmitting key 31 and its associated batteries 32 and 33. Let it therefore be assumed that the distant transmitter is operated to connect the positive side of a 105 line battery with the conductor 40 and the negative side of the same battery with the conductor 41. This positive current arriving over the conductor 40 will traverse the impedance coil 29, a conductor 22, the serially connected windings 1 and 2 of the relay D, a conductor 21, a resistance unit 35 of the artificial line C, a conductor 24, the serially connected windings 3 and 4 of the relay D, a conductor 23, the impedance 110 coil 30, thence returning over the line conductor 41 to the distant station. For purpose of description let it be assumed that at the instant just preceding inception of the positive impulse the tongue 5 of the relay D was biased to engage its negatively connected contact stop, thereby causing the condenser 14 to be negatively charged and also establishing steady current of the same polarity through the coil 11 to set up stress 125 to relieve the major portion of the polarizing magnetic effect acting to retain the armatures 7-10 in their right-hand positions. This relatively neutral condition of the armatures of the relay permit an instant 130

response to the positive impulse through the line windings 1-4, and on the instant the tongue 5 separates from its negative stop the condenser 14 discharges through the windings 11 and 12, as already described, thereby causing the armatures 9 and 10 to act through the shaft 6 in aiding the armatures 7 and 8 to move the tongue 5 to its positively poled stop. On the instant the tongue 5 engages its positive stop the polarizing magnetism in each section of the relay is free to act with any portion of the positive impulse which may still be present in the windings 1-4 and also assisted by the condenser charging effect through the winding 12 in establishing a firm contact between these members. Such instant of firm contact may be considered as the period during which the condenser 14 is receiving a charge from the positive source, and on the condenser becoming fully charged the positive current through the coil 11 will become free to stress the armatures 9 and 10 against the polarizing strains which act to hold the moving members of the relay in their right-hand or positive positions, as already mentioned. It will, therefore, be clear that when the distant transmitter establishes a reversal of current with the line conductors so that the conductor 40 becomes negatively energized while the conductor 41 is positively poled, such current through the circuits already traced will set up operations in the relay D which will be identical to but reciprocal of the operations already described in connection with the positive impulse. Such current will result in the tongue 5 being moved to its right-hand or negative stop.

Referring now to the operations whereby telegraphic signals may be transmitted to the distant station the battery 32 may supply current over the key 31 to a duplex circuit one branch of which extends over the bridge arm resistance 25, the impedance coil 29, the line conductor 40 to the distant station and after passing through the line relay windings and associated circuits at that point this current returns over the line conductor 41, the impedance 30 and the resistance arm 28 to the opposite side of the battery 32. For the second branch of the duplex circuit current passes from the key 31 by way of the bridge resistance 26, the resistance 35 and bridge resistance 27 to the opposite side of the battery 32. Since the artificial line C is in electrical balance with the real line A, as already mentioned, current from the battery 32 by way of the duplex circuits just traced will not disturb a normal condition of zero potential between the conductors 21 and 22 or 23 and 24 whereby the windings 1-4 of the home relay D are connected to the system. In transmitting signals by means of the key

31 the batteries 32 and 33 may be alternately connected over the duplex circuits already traced, but due to the balance of these circuits neither of the batteries may disturb the normal position of the home relay. 70 Such changes in polarity over the line A will, however, be effective in operating the line relay at the distant station in a manner similar to that already described for operating the home relay D. 75

In a more strict description of the changes in current whereby the line relay D may be operated, it will be pointed out that if an impulse of positive current from the distant station A arrives by way of the conductor 40 at a time the key 31 is connected with the negative battery 32 this battery and the distant battery will form an accumulative couple to increase the strength of current through the line loop 80 A, without affecting the strength of the current from the battery 32 as present in the artificial line C. Such preponderance of current in the bridge arms 25 and 28 will cause a difference of potential between the conductors 21 and 22 and between the conductors 23 and 24, thereby setting up currents in the windings 1 and 2, and 3 and 4, respectively, which will act to bias the relay D to its positive side. In case the distant key is positioned to send negative current by way of the conductor 40 while the key 31 is in engagement with the negative battery 32, the home and the distant battery then form a differential couple through 90 the line loop and thereby cause cessation of current through this circuit. Since the current condition through the circuits of the artificial line C remain undisturbed this electrical condition in the circuits of the real line sets up a difference of potential of inverse polarity to that already described through the windings 1-2 and 3-4; therefore, the moving parts of the relay D will be biased to their negative position. Results similar 105 to the responses of the relay D as described will be had whether the key 31 may be connected with the battery 32 or with the battery 33. Such changes of current condition are in accordance with the usual phenomenon which characterizes the working of 110 duplex telegraphs. 115

A further advantage of the relay apparatus employed in the present invention may be mentioned as a bettering of the operating efficiency of the relay. Aside from the obvious advantage in the cubical space as the volume of the windings as compared with a compound-wound relay, the absence of any transformer effect between the exteriorly connected windings 1-4 and the locally connected windings 11 and 12 materially increases the efficiency or sensitivity of the device. In compound-wound relays the inductive action is invariably dif- 125 130

ferential with respect to the inducing current; therefore, it will be obvious that the multiple-section self-aiding relay above described may be readily applied in any situation that may require a supersensitive relay.

What is claimed is:

1. A telegraph receiving system comprising in combination with a line circuit, a plurality of electromagnets, armatures therefor, a common suspension means of non-magnetic material connecting said armatures together, one of said electromagnets being responsive to signals in said line circuit to cause an initial movement of said armatures and a local circuit including another of said electromagnets and controlled by said initial movement to aid said line signals in moving said armatures.
  2. A telegraph receiving system comprising a plurality of polarized electromagnetic structures, an armature individual to each of said structures, pivotally supported non-magnetizable means for joining said armatures, a line circuit through which one of said electroresponsive structures is energized to cause an initial movement of said armatures, a local circuit including contacts controlled by said movement for energizing another of said electroresponsive structures to aid in the movement of said armatures.
  3. A telegraph receiving system comprising a polarized relay having an armature responsive to telegraphic signals, a polarized electromagnet having its armature connected to the armature of said polarized relay by a common pivotal support but magnetically separated therefrom, a local circuit including adjustable inductance and capacity and means controlled by an initial movement of the armature of said polarized relay to energize said local circuit and said polarized electromagnet to aid in the movement of the armature of said polarized relay.
  4. A telegraph receiving system comprising a polarized relay responsive to signaling
- impulses, a polarized electromagnet having its armature fixed to the armature of said polarized relay, a pivotal support common to said armatures, a local circuit controlled by said polarized relay to render said polarized electromagnet effective to aid in the operation of said polarized relay, and means included in said local circuit to vary the time constant of operation of said polarized electromagnet to correspond to the time constant of operation of said polarized relay.
5. In a telegraph system, an electrically balanced telephone circuit, an artificial line having electrical characteristics corresponding with said telephone circuit, a relay, ratio resistances connected intermediate each conductor of said metallic circuit and said artificial line, impulse transmitting means bridged on said circuits at a point intermediate said ratio resistances, a plurality of windings for said relay respectively bridged on the ratio resistances of each side of said metallic circuit to render the relay unresponsive to impulses from said transmitter, an electromagnet controlled by said relay, and means controlled by said electromagnet for aiding in the operation of said relay.
6. In a system of simultaneous telegraphy and telephony, an electrically balanced telephone circuit, an artificial line, a relay, a plurality of windings for said relay respectively connected intermediate each conductor of said metallic circuit and said artificial line, a transmitter for establishing impulses in accumulative relation over said metallic circuit to operate said relay, an electromagnet controlled by said relay inductively insulated both electrically and magnetically from said relay, and means controlled by said electromagnet to aid in the operation of said relay.

In witness whereof I hereunto subscribe my name this 29th day of December, A. D. 1917.

JOHN H. BELL.
